UNITED STATES PATENT OFFICE.

EDWARD THOMAS JENKINS, SR., OF BROOKLYN, NEW YORK, ASSIGNOR TO HIMSELF AND BENJAMIN BLEIER, OF SAME PLACE.

BOTTLE-STOPPER.

SPECIFICATION forming part of Letters Patent No. 567,394, dated September 8, 1896.

Application filed May 23, 1895. Renewed February 18, 1896. Serial No. 579,803. (No model.)

To all whom it may concern:

Be it known that I, EDWARD THOMAS JENKINS, Sr., a citizen of the United States, residing at Brooklyn, in the county of Kings and State of New York, have invented a new and useful Improvement in Bottle-Stoppers, of which the following is a specification.

My invention relates to an improvement in bottle-stoppers, the essential object of which is to prevent the refilling of bottles after they have been once emptied. With many brands of reputable liquids it has heretofore been a custom of irresponsible persons after the originally-filled bottles have been emptied to refill them with spurious liquids that are palmed off for the genuine material under the name upon the bottles. My invention is designed to prevent this practice.

In carrying out my invention I employ a glass cap connected to the bottle-mouth and adapted to be corked and sealed air-tight at its end, a plug in the mouth of the bottle, a hollow perforated conical guard within the glass cap, and a main ball and several auxiliary balls within the conical guard and resting upon the plug. After the bottle is filled the plug is placed in the bottle-mouth, the conical guard and balls are placed over the plug, and the glass cap is connected and cemented in place, and sealed so as to be air-tight. When the bottle is to be emptied, the air-tight seal is broken and the bottle turned upside down, when the balls will fall down in the conical guard and the plug come away from the bottle-mouth, permitting the liquid to discharge through the perforations in the conical guard. The bottle cannot be refilled in an upside-down position because the air cannot be got out, and when placed in a vertical or horizontal position the weight of the balls within the conical guard forces the plug to its seat in the mouth of the bottle and effectually shuts off ingress thereto.

In the drawings, Figure 1 is a vertical section showing my improvement. Fig. 2 is a cross-section at $\alpha\alpha$ of Fig. 1, and Fig. 3 is a section similar to Fig. 1 with the parts in a horizontal position.

The glass bottle a may be of any desired form, and I provide the same with a rim a' , that is preferably internally threaded. I em-

ploy a tapering cap b , preferably of glass, having a base exteriorly threaded and adapted to screw into the rim a' and to be firmly connected thereto by an intervening layer of cement 2. The outer end or mouth of the cap b receives the cork 3 and is covered with sealing-wax 4 in sealing the contents of the bottle to make the same air-tight. A plug c , of wood, rubber, or other suitable material, fits into the mouth of the bottle. A conical guard d , having a flanged base and perforations 5, and preferably made of metal, fits within the cap b , the flanged base being clamped within the rim a' beneath the base of the cap b , and within the said cone I place a large main ball e and several small auxiliary balls f . The balls are preferably of metal and the main ball of about the same diameter as the head of the plug and nearly filling the larger part 70 of the hollow conical guard, while the auxiliary balls f are much smaller. In putting the parts together after the bottle is filled with liquid the plug c is placed in the mouth of the bottle, the conical guard d , with the balls 75 e,f inclosed, is put over the plug c , the cap b is screwed and cemented to place, and the cork 3 and sealing 4 applied to close and seal the bottle air-tight. When this sealing is broken and the bottle turned over the contents are delivered through the perforated 80 conical guard and the bottle emptied. Any future effort to refill the bottle when turned upside down would fail because of the body of air therein, and an effort to refill it when 85 placed vertically or when turned on one side horizontally would also fail, because in said position the weight and pressure of the balls keep the plug to its seat, and the only way the bottle can be refilled is by removing the 90 cap b by undoing the cemented joint 2, which, as such joints are generally made, means the destruction of the bottle.

I claim as my invention—

1. The combination with a bottle and a cap 95 adapted to be connected to the bottle and to be closed or sealed air-tight, of a tapering plug for the mouth of the bottle, a hollow perforated conical guard located above the plug and having a flange by which it is held to the 100 bottle, a large ball nearly filling the larger part of the hollow guard and several smaller

balls within the guard between the large ball and the small end of the guard, whereby the small balls act upon the large ball to assist the same in keeping the plug to its seat and 5 also in holding the ball centrally over the plug, substantially as specified.

2. The combination with the bottle *a*, having an internally-threaded rim *a'*, of a tapering cap having an exteriorly-threaded base to 10 be connected and cemented to the said rim *a'*, and adapted for a cork and air-tight sealing, a tapering plug *c* for the mouth of the bottle,

a perforated cone *d* having a flanged base to be clamped and secured between the bottle and base of the cap, a large ball *e* and auxiliary balls *f* within the cone and acting by their weight to keep the plug to its seat, substantially as set forth. 15

Signed by me this 18th day of May, A. D. 1895.

EDWARD THOMAS JENKINS, SR.
